[57] CLAIM

The ornamental design for a contoured vibrator, as shown.

DESCRIPTION

FIG. 1 is a perspective view of a contoured vibrator embodying our new design;

FIG. 2 is a front elevational view thereof;

FIG. 3 is an end elevational view looking from the right of FIG. 1;

FIG. 4 is a top plan view thereof; and,

FIG. 5 is a rear elevational view thereof.

The broken lines shown in FIG. 5 represent top-stitching.
